HEATING SYSTEM

William W. Hallinan, Mendota, Ill.

Original application October 16, 1939, Serial No. 299,616. Divided and this application December 11, 1941, Serial No. 422,475

9 Claims. (Cl. 236—10)

The present invention relates to heating systems, and is particularly concerned with heating systems of the hot air type, in which the air is to be circulated throughout the house or other space to be heated by means of a forced feed.

The present application is a division of my prior application, Ser. No. 299,616, Heating systems, filed October 16, 1939, now Patent Number 2,289,287, dated July 7, 1942.

The heating systems of the prior art of this character are subject to the disadvantage that they are either complicated or they are so constructed that the volume of air circulated by the blower or fan must be adjusted to take care of the maximum heating load, which inevitably results in a higher operating temperature for the furnace, too great a volume of air put out by the fan when there is but a little demand for heat, and a blast of cold air from the furnace soon after the fan begins to operate, when the furnace is not operating at maximum heating load.

One of the objects of the invention is the provision of an improved heating system in which the fan may be operated continuously, or it may commence its operation at a relatively low temperature, and in which the speed of operation of the fan is continuously modulated from low speed at small furnace output to maximum speed at maximum furnace load.

Another object of the invention is the provision of an improved heating system of the class described, in which the operating temperature may be reduced to a lower value than the devices of the prior art, thus reducing the furnace losses at the stack and losses in the cellar, and providing a more efficient heating system.

Another object of the invention is the provision of an improved heating system of the class described, which is adapted to operate within a smaller range of temperature variation for the purpose of maintaining a more uniform temperature in the rooms to be heated, and for the purpose of eliminating any possibility of a blast of cold air.

Another object of the invention is the provision of an improved heating system of the class described, by means of which the volume of air circulated in the system is dependent upon the temperature of the circulating air or of the air in the plenum chamber in the furnace, so that a maximum efficiency of distribution of heat from the furnace is achieved and the circulating system is adapted at all times to circulate a volume of air which is required to carry away the heat from the furnace.

Another object of the invention is the provision of an improved variable speed driving system for air circulating fans, which is efficient, economical, and capable of manufacture and installation at a reasonable cost.

Other objects and advantages of the invention will be apparent from the following description and the accompanying drawings, in which similar characters of reference indicate similar parts throughout the several views.

Referring to the two sheets of drawings accompanying the specification:

Fig. 1 is a diagrammatic vertical sectional view of a hot air furnace embodying the present heating system;

Fig. 2 is a diagrammatic top plan view of the motor and blower, with the furnace in partial section;

Fig. 3 is an axial sectional view, taken on the plane of the line 3—3 of Fig. 1, looking in the direction of the arrows;

Fig. 4 is a fragmentary end elevational view of the adjustable nut, by means of which the tension of the V pulley is adjusted.

Referring to the drawings, 10 indicates in its entirety the installation which includes the furnace 11, such as a gas furnace, an oil burner, or a coal stoker type, controlled by room thermostats and auxiliary equipment so as to be turned on responsive to the heat demand in the rooms.

The furnace casing is indicated at 12, and it is provided with the usual bonnet 13, having hot air outlets to the rooms at 14.

The cold air inlet to the furnace casing is at 15, the outlet of a fan or blower 16 preferably of the centrifugal type, having a suitable centrifugal impeller shaft 17, which is provided with a V pulley 18.

The discharge pipe from the blower 16 passes through a hole in the wall of the furnace housing. The blower, of course, takes in air within the chamber where it is located, through intake apertures at the end of the shaft 17. Thus the only cold air inlet to the furnace is through the blower 16, which takes its cold air in from the upper conduit 27.

The blower 16 is adapted to be driven by means of a V belt 19 of constant width, which is driven by a variable diameter pulley 20 carried by the shaft 21 of a substantially constant speed motor 22.

The blower 16 and motor 22 and other auxiliary equipment may be installed in a filter housing 23, comprising a metal housing of substantially rectangular shape, connected to the fur-

nace casing 12, and having a screened inlet at 24. Supporting angles 25 in the filter housing may support a plurality of suitable air filters 26, through which the air passes to the inlet of the centrifugal blower 16, said blower being provided with an inlet at one or both of the ends of its housing, surrounding the shaft 17. Suitable cold air conduits 27 from the rooms are in communication with the cold air inlet 21 to the filter housing 23.

The blower motor 22 is preferably movably mounted by having its base 28 secured to a pivotally mounted base 29, which is carried by a bracket 30, by means of a pivot shaft 31.

A tension spring 32 has its upper end adjustably secured to a bracket 33, carried by the blower 16, and its lower end secured to a bracket 34, carried by the motor base 29. Thus spring 32 may have its tension adjusted by means of the nuts 35 on the threaded end of the spring, and the spring tends to urge the motor pivotally about the center of the shaft 31 in a counterclockwise direction so as to give the belt 19 a suitable tension.

The variable diameter pulley 20, carried by the motor shaft 21, is illustrated in detail in Fig. 3. It preferably consists of a pair of pulley sections 36 and 37. The pulley sections are provided with the radially extending flanges 38 and 39, which have the opposed frusto-conical surfaces 40 and 41, forming a substantially V-shaped groove 42 for receiving the wedge-shaped leather V belt 19.

The pulley section 36 preferably has a centrally located circular bore 43 in the cylindrical hub 44, and the bore 43 is adapted to receive the motor shaft 21, to which the section 36 is secured by a set screw 45 or a suitable key.

The end of the hub 44 may have a reduced threaded extension 46 for slidably receiving the spring seat 47 and receiving the threaded nut 48 and lock washer 49. The hub 44 is preferably provided with an outer cylindrical surface 50, formed with a keyway 51 for receiving the key 52 of substantially rectangular cross section, which is also received in a groove 53 in the pulley section 37.

The key 52 may have a tight frictional fit in one of the grooves 51 or 53 and be readily slideable with respect to the other of said grooves. In other words, the key may be secured to the section 36 or the section 37, but section 37 is adapted to slide freely relative to the section 36.

The pulley section 37 is provided with the tubular or cylindrical extension 54, having an inner cylindrical bore 55 slidably mounted on the hub 44. The tubular extension 54 may have a cylindrical enlargement at 56, engaging the inside of a compression coil spring 57 of helical form, and the end of the coil spring may engage against the outer face 58 of the pulley section 54.

The opposite end of the coil spring engages the spring seat 47, which may consist of a cast metal member having a hub 59, an outwardly extending body flange 60, and a cylindrical retaining flange 61.

The hub 59 has a bore 62 for receiving the reduced threaded portion 46 of the pulley section 36. The spring seat 47 may be mounted for sliding movement on the reduced portion 46, but is prevented from rotation by a rib or key 63, located in an axially extending slot 64. The outwardly extending flange 60 may be of frusto-conical form, and there may be a radial flange 65 for engaging the under side of the lock washer 49. The lock washer 49 may be provided with a

plurality of radial slots 66, and the spring seat 47 with a rib 67 for engaging in any one of those slots.

It will be evident that the tension of the spring 57 may be adjusted by the position of the nut 48. The nut 48 may be locked in its adjusted position by the rib 67, and an inward pressure of the spring seat 47 against the spring 57 will remove the rib 67 from its groove 66 and permit an adjustment of the nut 48.

The operation of the spring pulley is as follows:

The effective diameter of the pulley depends upon the point to which the belt 19 is drawn into the groove 42. This in turn depends upon the relative positions of the pulley sections 36 and 37, and the pulley sections 36 and 37 may take a position which depends on the action of the belt 19 and the belt tension.

When the motor 22 is pivoted toward the left in Fig. 1, or counterclockwise, the belt 19 is drawn farther into the V groove 42, the spring 57 giving way and permitting the section 37 to recede from the section 36. This naturally decreases the effective diameter of the adjusted pulley 20 and changes the speed of drive of the blower because the driving pulley 20 is smaller relative to the size of the driven pulley 18.

When the motor 22 moves to the right or pivots in the clockwise direction, the center of the pulley 18 being fixed, and the belt 19 being of constant length, the belt is permitted to ride out farther in the groove 42, the spring 57 forces the pulley sections 36, 37 closer together, and the effective diameter of the adjustable pulley 20 is increased. This increases the speed of rotation of the blower 16 because the size of the pulley 20 relative to that of the pulley 18 has been increased.

The position and movement of the motor 22 on its pivotal support 31 is preferably controlled by pressure responsive or thermally responsive means, such as a metal bellows 70.

The blower 16 and motor 22 are carried by a base 71, which may have an upwardly extending bracket 72 for fixedly supporting one end of the extensible metal bellows 70. The other, or right hand, end of the bellows has its face provided with a hub 73, connected to a connecting rod 74, which is pivotally secured by a pin or bolt 75 to a pivoted bracket 76, carried by the motor 22.

The bellows 70 comprises a pressure responsive device, but the pressure is preferably derived from a thermally expansible fluid which is contained in the bellows and which may be subjected to heat in any of a plurality of different ways.

For example, the furnace casing 12 is provided with a conduit 81 leading from the top of the casing and extending over to the thermostat 70, where it has its discharge opening 82 located to discharge hot air from the plenum chamber on the thermostat 70. Here the circulation of the air is caused by the blower 16, and hot air from the plenum chamber 79 is immediately blown on the thermostat 70 so that the thermostat is responsive to the temperature of the air delivered from the plenum chamber.

The operation of the invention is as follows: The furnace 11 may be considered to be any source of heat, such as a furnace having an oil burner, a gas burner, or a coal stoker, or the furnace may be replaced by an ordinary radiator forming a part of the steam or water heating system. In the latter case the present air conditioning system would be a separate unit, applied only to one or more of the radiators for the pur-

pose of providing a continuous and modulated circulation of air in a room.

The thermostatic control for the motor 22 may include a room thermostat for turning on the motor at a predetermined temperature, or the motor may be controlled exclusively by a furnace thermostat (not shown).

In other cases the motor 22 may operate continuously at a low rate of speed, while the heating system is in operation, the motor circuit being closed by a plenum chamber thermostat (not shown) when the plenum chamber reaches a predetermined value, and thereafter the speed of the motor is controlled by means of the thermostat 70.

When the plenum chamber 79 delivers air at a moderate temperature, the thermostat 70 is contracted, and the motor 22 is pivoted over counterclockwise in Fig. 1, a position to which it is urged by the spring 32.

The spring 32 is strong enough so that it is adapted to overcome the axial pressure of the spring 57 when the thermostat 70 is not working to force the motor in the opposite direction, and therefore the belt 19 is drawn deeply into the groove 42 of the pulley, and the pulley has its smallest effective diameter. Under these conditions the blower will be driven at a low speed because the driving pulley is smaller, and only a small volume of air will be driven through the furnace and out of the air registers.

As the temperature of the air delivered from the plenum chamber increases, the thermostat 70 expands, moving the motor 22 toward the right on the pivot 31, and the length of the belt 19 being constant, the belt is permitted to ride outward in the groove 42, giving the pulley 20 a larger effective diameter. This increases the speed of rotation of the blower, and a larger volume of air is delivered, depending upon the temperature of the air in the plenum chamber.

The characteristics of the thermostatic control and the biasing springs may be made such that the relation between the temperature and volume of air delivered is substantially a straight line curve, and the volume of air delivered is substantially proportional to the temperature expressed in this manner.

When the furnace is very hot, a larger volume of air passes through it, and more heat is removed from the furnace, which is in accordance with its increased rate of production of heat. Thus the air blower system, which is the means of transferring heat from the furnace to the rooms to be heated, operates more efficiently than the devices of the prior art, and delivers more heat when there is more heat to be delivered. Yet the speed of operation of the blower and the temperature at which the motor is started need not be set so high as in the devices of the prior art where a blower usually is set at maximum speed in order to take care of the full load of the furnace.

The present device not only takes care of full load of heat delivered from the furnace, but also delivers a moderate amount of heat when the furnace is producing a moderate amount of heat, and the amount of heat delivered by the blower to the rooms in the form of hot air is continuously and uniformly graduated from a small amount to maximum delivery.

While the thermostat in this case is not subjected to the temperature of the air in the plenum chamber, it is responsive to the temperature of the air delivered from the plenum chamber, which

is substantially the same thing as being responsive to the air coming directly from the furnace into the room or space to be heated.

As one of the objects of the invention is to prevent the blowing of cold air into the room at a rate of speed, it follows that it is advantageous to control the speed of the blower responsive to the temperature of the air delivered from the plenum chamber.

10 It will thus be observed that I have invented an improved heating system which may be embodied in all types of furnaces or utilized with hot water or steam radiators for single units used in rooms.

15 My heating system provides a continuous and modulated change of delivery of heated air by means of a blower, the volume of which changes continuously and uniformly with changes in temperature of the furnace or the air to be delivered. Stratification is eliminated, and such a blower may be operated continuously without causing a cold blast of air at any time because when the air is cooler, the speed of rotation of the fan is lower, and a smaller volume of air, 20 which is not so hot, may be delivered without causing the sensation of a cold blast.

25 While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

30 1. In a heating system, the combination of a source of heat with an air housing surrounding said source, and having a cold air inlet and a hot air outlet, the course of circulation of air through said cold air inlet and hot air outlet including an enclosed space to be heated and also including a blower for effecting a forced circulation, electric motor means for driving said blower, and thermostatic means controlled by heat received from said source of heat for continuously and uniformly varying the speed of operation of the blower from a minimum at low temperatures to a maximum at high temperatures, 35 whereby the volume of delivery of heated air from said housing is varied according to the amount of heat produced by said source, said latter means including a pulley of variable diameter for driving said blower, the effective diameter of said pulley being controlled by said thermostatic means, said thermostatic means comprising an expandible metal chamber and said system having a conduit leading from the housing for blowing heated air on said thermostatic means when the system is operating.

40 2. In a heating system, the combination of a source of heat with an enclosure about said source forming a plenum chamber, said enclosure having a cold air inlet, a hot air outlet, and a blower in communication with said plenum chamber, said blower being driven by an electric motor by means of a pair of V pulleys, and a wedge-shaped belt, one of said pulleys having a pair of movable sections spring pressed together to form 45 a pulley of variable diameter, and thermostatic means for controlling the relative position of said pulleys whereby the speed of rotation of the blower is thermostatically controlled, said motor being pivotally mounted, and said thermostatic means acting against said motor and against a

fixed abutment whereby the thermostatic means is adapted to move the motor and change the distance between the centers of said pulleys to cause the wedge-shaped belt to engage the sectional pulley at different effective diameters.

3. In a heating system, the combination of a source of heat with an enclosure about said source forming a plenum chamber, said enclosure having a cold air inlet, a hot air outlet, and a blower in communication with said plenum chamber, said blower being driven by an electric motor by means of a pair of V pulleys, and a wedge-shaped belt, one of said pulleys having a pair of movable sections spring pressed together to form a pulley of variable diameter, and thermostatic means for controlling the relative position of said pulleys whereby the speed of rotation of the blower is thermostatically controlled, said motor being pivotally mounted, and said thermostatic means acting against said motor and against a fixed abutment whereby the thermostatic means is adapted to move the motor and change the distance between the centers of said pulleys to cause the wedge-shaped belt to engage the sectional pulley at different effective diameters, and spring means acting against said thermostatic means for maintaining the belt in a taut condition.

4. In a heating system, the combination of a source of heat with an enclosure about said source forming a plenum chamber, said enclosure having a cold air inlet, a hot air outlet, and a blower in communication with said plenum chamber, said blower being driven by an electric motor by means of a pair of V pulleys, and a wedge-shaped belt, one of said pulleys having a pair of movable sections spring pressed together to form a pulley of variable diameter, and thermostatic means for controlling the relative position of said pulleys whereby the speed of rotation of the blower is thermostatically controlled, said motor being pivotally mounted, and said thermostatic means acting against said motor and against a fixed abutment whereby the thermostatic means is adapted to move the motor and change the distance between the centers of said pulleys to cause the wedge-shaped belt to engage the sectional pulley at different effective diameters, and spring means acting against said thermostatic means for maintaining the belt in a taut condition, the sections of said pulleys being spring pressed together by a spring of less strength in its environment than the latter spring means.

5. A blower controlling system for hot air furnaces, comprising a blower provided with a driven pulley of the V-type, a support carrying said blower, a constant speed driving motor movably mounted on said support, and having a V-pulley for driving the blower, a V-belt embracing said pulleys, one of said pulleys comprising a pair of relatively movable sections spring pressed together to provide a groove of varying width and varying effective diameter, and means for controlling the speed of drive of said blower, comprising means for acting on said motor and moving it relative to said support to cause a variation in the effective size of said variable diameter pulley by variation of the distance between the pulley centers.

6. A blower controlling system for hot air furnaces, comprising a blower provided with a driven pulley of the V-type, a support carrying said blower, a constant speed driving motor movably mounted on said support, and having a V-pulley

for driving the blower, a V-belt embracing said pulleys, one of said pulleys comprising a pair of relatively movable sections spring pressed together to provide a groove of varying width and varying effective diameter, and means for controlling the speed of drive of said blower, comprising means for acting on said motor and moving it relative to said support to cause a variation in the effective size of said variable diameter pulley by variation of the distance between the pulley centers, said latter controlling means comprising a pressure responsive bellows having one end fixedly secured to said support, and the other secured to said motor.

7. In a heating system, the combination of a heater with an enclosure for receiving the air to be heated, said enclosure having a cold air inlet and a hot air outlet, a motor-driven blower having its outlet communicating with the cold air inlet of said enclosure and having its inlet located to communicate with a cold air pipe, thermostatic means for controlling the speed of actuation of said blower by its motor, and a conduit communicating with said enclosure and adapted to receive hot air from said enclosure, said conduit conducting the hot air to said thermostatic means whereby the thermostatic means is made responsive to the temperature of air discharged from said enclosure.

8. In a heating system, the combination of a heater with an enclosure for receiving the air to be heated, said enclosure having a cold air inlet and a hot air outlet, a motor-driven blower having its outlet communicating with the cold air inlet of said enclosure and having its inlet located to communicate with a cold air pipe, thermostatic means for controlling the speed of actuation of said blower by its motor, and a conduit communicating with said enclosure and adapted to receive hot air from said enclosure, said conduit conducting the hot air to said thermostatic means whereby the thermostatic means is made responsive to the temperature of air discharged from said enclosure, said blower motor and thermostatic means being located in an enlargement of a conduit serving as the cold air inlet to the system.

9. In a heating system, the combination of a heater with an air enclosure having its walls spaced from said heater, for receiving the air to be heated, said enclosure having a cold air inlet and a hot air outlet, a motor driven blower having its outlet communicating with the cold air inlet of said enclosure, a motor for driving said blower, an auxiliary housing enclosing said motor and blower and having a cold air inlet, thermostatic means for regulating and controlling the speed of rotation of said blower by said motor, and a by-pass conduit extending from a point adjacent the top of said first-mentioned heater enclosure and discharging into said second-mentioned enclosure adjacent said thermostatic means for subjecting the thermostatic means to air discharge from the heater enclosure, said thermostatic means being arranged to increase the speed of rotation of said blower as the temperature of the air discharged by said by-pass increases and to decrease the speed of rotation of said blower as the temperature of the air discharged from said by-pass decreases, whereby the motor and blower may be located in a relatively cool portion of the installation and may be directly controlled by said thermostatic means responsive to air discharged from the heater enclosure.

WILLIAM W. HALLINAN.
